(57) **CLAIM**

The ornamental design for a bottle, as shown and described.

DESCRIPTION

FIG. 1 is a top, front perspective view of a first embodiment of a bottle showing our new design;

FIG. 2 is a front elevational view thereof, the rear elevational view being a mirror image;

FIG. 3 is a left side elevational view thereof, the right side elevational view being a mirror image;

FIG. 4 is a top plan view thereof;

FIG. 5 is a bottom plan view thereof;

FIG. 6 is a top, front perspective view of a second embodiment of a bottle showing our new design;

FIG. 7 is a front elevational view thereof, the rear elevational view being a mirror image;

FIG. 8 is a left side elevational view thereof, the right side elevational view being a mirror image;

FIG. 9 is a top plan view thereof; and,

FIG. 10 is a bottom plan view thereof.

The dash lines shown in the drawings are for illustrative purposes only and form no part of the claimed design.

The dot-dash-dot lines shown in the drawings define the boundary of the claim and form no part of the claimed design.
